(57) **CLAIM**

The ornamental design for a fuel filter conversion plate, as shown and described.

DESCRIPTION

FIG. 1 is a rear perspective view of the fuel filter conversion plate;

FIG. 2 is a front, bottom perspective view of the fuel filter conversion plate;

FIG. 3 is a rear elevation view of the fuel filter conversion plate;

FIG. 4 is a top plan view of the fuel filter conversion plate;

FIG. 5 is a front elevation view of the fuel filter conversion plate;

FIG. 6 is a bottom plan view of the fuel filter conversion plate; and,

FIG. 7 is a left side elevation view, the right side being a mirror image thereof.

The broken lines shown in the drawings are for the purpose of illustrating portions of the fuel filter conversion plate that form no part of the claimed design.
